UNITED STATES PATENT OFFICE.

FRANK S. CROWELL, OF TOLEDO, OHIO, ASSIGNOR TO THE EDWARD N. RIDDLE CO.,
OF TOLEDO, OHIO, A CORPORATION OF OHIO.

DESIGN FOR A CAST PLATE FOR LIGHTING FIXTURE.

Application filed April 19, 1924. Serial No. 9,334. Term of patent 7 years.

To all whom it may concern:

Be it known that I, FRANK S. CROWELL, a citizen of the United States, and residing at Toledo, in the county of Lucas and State of Ohio, have invented a new, original, and ornamental Design for Cast Plate for Lighting Fixture, of which the following is a specification, reference being had to the accompanying drawing, forming part thereof.

Fig. 1 is one half of an inverted plan view and Fig. 2 is a side view of cast plate showing my new design.

I claim:

The ornamental design for a cast plate for lighting fixture as shown.

FRANK S. CROWELL.
